UNITED STATES PATENT OFFICE.

ARTHUR J. WILLIAMSON, OF BROOKLYN, NEW YORK.

INTERNAL-COMBUSTION ENGINE.

Application filed October 5, 1920. Serial No. 414,942.

To all whom it may concern:

Be it known that I, ARTHUR J. WILLIAMSON, a citizen of the United States, and a resident of the borough of Brooklyn, county 5 of Kings, city and State of New York, have invented a new and useful Internal-Combustion Engine, of which the following is a specification.

The invention relates to internal combustion engines, and the object is to provide an 10 advantageous construction involving oppositely moving power members whereby the effect of a long-stroke motor is secured without sideslap. The invention may accordingly be said to comprise the parts, improvements and combinations hereinafter 15 described and more particularly pointed out in the appended claims.

In the accompanying drawings, forming 20 part hereof:

Figure 1 is a vertical section in the plane of the axes through an engine comprising two units, one of the units being shown in full section with the exception of its piston, 25 and the other being mainly in elevation inside of its receiving cylinder;

Fig. 2 is a vertical axial section through one of the units, in a plane at right angles to that of Fig. 1;

Figs. 3 and 4 are horizontal sections on the lines 3-3 and 4-4, respectively, of Fig. 2; and

Figs. 5 to 8 are diagrams of operation.

Each of the units has a stationary cylinder 35 casting 1, containing an eccentric cylinder bore 2, and a spark-plug chamber 3 at one side of the cylinder bore, the cylinder bore and spark-plug chamber being in open communication at the top. Suitable water- 40 cooling spaces 4 are also included in each cylinder casting; and slotted exhaust ports 5 open from the upper part of the bore into exhaust passages 6 passing downward through the water-spaces, and emerging to- 45 ward the bottom at 7. The lower part of each spark-plug chamber is open at the outer side, as seen in Fig. 2, for insertion and removal of the spark-plug 8, which is screwed upward into an opening in a contraction of 50 the upper part of the chamber.

A power piston 9 works inside each cylinder-bore, and is connected with the crank-shaft 10 by a connecting rod 11.

Each unit also includes a power head 12, 55 which moves oppositely to the piston, united with which head is a skirt 13 working on

the cylindrical exterior of the cylinder casting 1, the skirts being connected with the crank-shaft by connecting rods 27, working on suitable pivot portions 28 of the sleeves. 60

A stationary receiving cylinder 14, bolted at the bottom with flanges of the cylinder casting and the crank-case 15, surrounds the head 12 and its skirt 13, which work therein. An intake port in the head is com- 65 manded by an inwardly opening, pressure-controlled valve 16, biased to closing by a light spring 17. The two receiving cylinders are connected at the top by a transfer conduit 18, which is connected with the car- 70 buretor by a conduit 19 containing a check-valve 20.

The exhaust of each unit is controlled by a sleeve valve 21 reciprocating between the piston and the cylinder bore, and containing 75 exhaust ports 22 to co-operate with those of the cylinder casting. These sleeves are operated from a half-time shaft 23 by eccen- 80 trics 24 and connecting links 25. Half-time gearing 26 between the crank-shaft and valve shaft is seen in Fig. 1.

The connections are so disposed that the pistons and heads of the two units operate in unison, that is to say, in both units these members move toward each other at the 85 same time and apart at the same time. The eccentrics for the exhaust sleeve valves, however, are set 180° apart on the half-time shaft, so that their openings and closings are two strokes apart in the cycle of opera- 90 tions. Thus, in the two units, the cycles are as follows:

Firing—intake.

Exhaust—compression.

Intake—firing.

Compression—exhaust.

When the power members approach each other in one unit exhaust takes place, and at the same time a charge is compressed between the approaching members of the other 100 unit. When the members of the first unit separate in the succeeding intake stroke, the other power members are being driven apart in the firing stroke.

The diagrams illustrate the cycle in one 105 of the units. Fig. 5 shows the beginning of the firing stroke; Fig. 6 the beginning of the exhaust stroke; Fig. 7 the beginning of the intake stroke; and Fig. 8 the beginning of the compression stroke. The 110 intake valve is held closed by the internal pressure except on the intake stroke, when

the partial vacuum between the separating power members causes it to open. When the two heads 12 move downward in the receiving cylinders 14, fuel mixture is drawn into these cylinders past the check valve 20; and when the heads move up together, the contents of one of the receiving chambers is displaced through the conduit 18 into the other, whence the joint contents pass the open intake valve 16 of this head into the widening space between it and the corresponding piston. The gases in the receiving chambers are preheated, and receive some initial compression.

15 Packing rings are placed in the relatively sliding surfaces where necessary.

What I claim as new is:

1. In an internal combustion four-cycle engine, the combination of an inner cylinder, a power piston operating therein, a power head moving oppositely to and encircling said piston and cylinder and having a skirt outside of said cylinder, a crank-shaft and connecting rods between the same and the piston and skirt, an outer receiving cylinder in which the head and its skirt operate, an intake valve in said head, and a reciprocating sleeve valve controlling the exhaust operating between the piston and said inner cylinder.

2. In an internal combustion four-cycle

engine, the combination of an inner cylinder casting containing a cylinder bore, a spark-plug chamber and a water-cooling space, a power piston operating in said bore, a power head moving oppositely to the piston and having a skirt working on the outside of the cylinder casting, a crank-shaft and connecting rods between the same and the piston and skirt, an outer receiving cylinder in which the head and its skirt operate, an intake valve in said head, and a sleeve valve controlling the exhaust reciprocating between the piston and cylinder bore.

3. In an internal combustion four-cycle engine, the combination of two units; each comprising an inner cylinder, a power piston operating therein, a power head moving oppositely to the piston and having a skirt outside of said inner cylinder, an outer receiving cylinder in which the head and its skirt operate, a pressure-controlled intake valve in the head, and driven exhaust-valve means; the two receiving cylinders being in communication; a crank-shaft and connections whereby the pistons and integral heads of the two units operate in unison; and half-time connections whereby the operation of the exhaust valve means of the two units is appropriately displaced.

ARTHUR J. WILLIAMSON.
